UNITED STATES PATENT OFFICE.

WILLIAM STANLEY, OF GREAT BARRINGTON, MASSACHUSETTS, ASSIGNOR
TO STANLEY INSTRUMENT COMPANY, OF GREAT BARRINGTON, MASSA-
CHUSETTS, A CORPORATION OF MASSACHUSETTS.

INDICATING SYSTEM AND TIME-BEATER.

SPECIFICATION forming part of Letters Patent No. 741,735, dated October 20, 1903.

Application filed February 14, 1903. Serial No. 143,355. (No model.)

To all whom it may concern:

Be it known that I, WILLIAM STANLEY, a citizen of the United States, residing at Great Barrington, Berkshire county, Massachusetts, 5 have invented certain new and useful Improvements in Indicating Systems and Time-Beaters, of which the following is a full, clear, and exact description.

My invention relates to improvements in indicating systems and time-beaters forming a part hereof, and has for its object to attain simplicity in construction and accuracy of operation in such apparatus. It is capable of being used in various relations, such as electric time-keeping systems and electric meter systems.

The following is a description of my invention, reference being had to the accompanying drawings, in which—

20 Figure 1 is a side elevation of the improved time-beater. Fig. 2 is a plan of the same. Fig. 3 is a diagram of the improved system employing the time-beater and an electromagnetic device operated thereby. Fig. 4 shows 25 a modification of the time-beater short-circuiting mechanism.

Referring more particularly to the drawings, and first to the time-beater, A is the movable portion or armature of a magnetic circuit, of which B is a stationary portion having attached thereto the non-magnetic portion B'. The part A is mounted on the pivot-shaft C, carrying a balance-wheel C' and an iron spreading-disk C'', and normally tends to 35 return to a definite position slightly out of alignment with the part B by reason of the spring D, connected to the shaft C.

E constitutes a stationary winding or coil, supported at e e, for magnetizing the magnetic circuit, of which the parts A and B are portions.

F is a contact with which the cam G, mounted on the shaft C, comes into engagement as the shaft C oscillates. To the contact F one 45 side of the windings E is connected at H, the other side of the windings E being connected to the cam G by the conductor g.

R is a resistance in series with the windings E.

50 II' are mains of a constant-potential circuit.

The action of this device is as follows: When the device is disconnected from the mains I I' and the parts are at rest, the portion A is out of alignment with the portion B and the cam G is out of engagement with the contact F. If now the circuit from the mains I I' is completed, the coil E is energized, which magnetizes the armature A, the circuit being from the conductor I through the coil L, the coil E, the resistance R, to conductor I'. This causes it to swing into line with the portion B. As it makes this movement the cam G engages with the contact F, moving it slightly about the axis F'. This engagement short-circuits the windings E and deenergizes 65 the armature A, the short circuit being through conductor g, shaft C, cam G, fork F, to the point H. The armature A under the impulse already received swings forward until restrained by the spring D, which then 70 causes it to return. In returning it breaks engagement with the contact F, interrupting the short circuit and again temporarily energizes the windings E. As it swings it again engages with the contact F, again slightly 75 moving it, and continues in its course until again restrained and returned by the spring D. The impulses received by reason of the interruptions of the short circuit at the contact F keep the armature A oscillating so long 80 as the windings E are connected to a source of current, the slight movement of the contact F resulting in the windings E being energized only during the latter part of each half-oscillation. The periods of oscillations 85 are practically equal and the device constitutes a reliable time-beater.

Referring to the system as shown in Fig. 3, K is an electromagnetic device actuated or controlled by the time-beater and consisting of an energizing-coil L, free to move and retracted by a spring M and an armature N. The coil L carries a pawl O, which acts upon the ratchet-wheel P to cause it to revolve, and thus moves the pointer or other indicator Q. The coil L is connected in series with the coil E or so that it will be short-circuited whenever the coil E is short-circuited, the cam G being connected to the circuit between the coil L and the main I by the conductor g. 95 100

From this it will be seen that the coil L is energized and deenergized simultaneously with the coil E, so that the coil L receives an impulse once during each oscillation of the armature A. The reciprocation of the coil L causes the indicator Q to move through the action of the pawl O, thereby integrating the number of oscillations and indicating the time and constituting a time-keeping system.

10 In the modification shown in Fig. 4 the short-circuiting device consists of a lever S, pivoted at s and connected to the conductor g. This lever is moved to and fro by the pin T on the shaft C and makes and breaks contact with the terminals U U', which are connected to the main I'. The breaking and making of engagement with the contacts U U' energizes and deenergizes the exciting coil or windings, producing the results before described.

What I claim is—

1. A time-beater consisting of the combination of a magnetic circuit having an oscillating portion, a spring limiting the movement 25 of said oscillating portion in both directions and tending to return it to a definite position, windings for magnetizing said portion connected to a source of current, a short circuit around said windings, and means for periodically making and breaking said short circuit and thereby energizing and deenergizing said windings.

2. A time-beater consisting of the combination of a magnetic circuit having an oscillating portion normally out of alignment with the other part of said circuit, a spring limiting the movement of said oscillating portion in both directions and tending to return it to a definite position out of alignment with 35 the other part of said circuit, windings for magnetizing said magnetic circuit connected to a source of current, a short circuit around said windings, means for periodically making and breaking said short circuit and thereby 40 magnetizing and demagnetizing said magnetic circuit.

3. A time-beater consisting of the combination of a magnetic circuit having an oscillating portion normally out of engagement with 50 the other part of said circuit, a spring limiting the movement of said oscillating portion in both directions and tending to return it to a definite position out of alignment with

the other part of said circuit, windings for magnetizing said magnetic circuit connected 55 to a source of current, a short circuit around said windings, means for periodically making and breaking said short circuit, and thereby magnetizing and demagnetizing said magnetic circuit, and a resistance in series with 60 said windings and short circuit.

4. In combination an electromagnetic device having stationary and movable members with windings for energizing the same, a time-beater having a movable member and 65 windings for energizing the same, and means operated by said movable member for periodically energizing and deenergizing the windings of said time-beater and causing the movable member of said electromagnetic device 70 to oscillate.

5. In combination, an electromagnetic device having stationary and movable members with windings for energizing the same, a time-beater having a movable member and 75 windings for energizing the same and means operated by said second movable member for periodically short-circuiting the energizing-windings of said electromagnetic device and time-beater.

6. In combination, an electromagnetic device having stationary and movable members with windings for energizing the same, a time-beater having a movable member and windings for energizing the same and means 85 operated by said second movable member for periodically short-circuiting the energizing-windings of said electromagnetic device and time-beater and a resistance in series with 90 said windings and short circuit.

7. A device having a fixed period of oscillation consisting of a stationary member and relatively movable member forming parts of a magnetic circuit, windings for magnetizing the same, a circuit therefor, two terminals 95 connected to one side of said windings and a lever connected to the other side and means operated by said movable member for causing said lever to make and break contact with said terminals alternatively and a spring 100 tending to return said movable member to a definite position.

WILLIAM STANLEY.
